(57) **CLAIM**

The ornamental design for an intelligent vehicle terminal, as shown and described.

DESCRIPTION

FIG. 1 is a front perspective view of an intelligent vehicle terminal showing our design.

FIG. 2 is a rear perspective view of the intelligent vehicle terminal in FIG. 1.

FIG. 3 is a front elevation view of the intelligent vehicle terminal in FIG. 1.

FIG. 4 is a rear elevation view of the intelligent vehicle terminal in FIG. 1.

FIG. 5 is a left side elevation view of the intelligent vehicle terminal in FIG. 1.

FIG. 6 is a right side elevation view of the intelligent vehicle terminal in FIG. 1.

FIG. 7 is a top plan view of the intelligent vehicle terminal in FIG. 1; and,

FIG. 8 is a bottom plan view of the intelligent vehicle terminal in FIG. 1.

The broken lines in the drawings illustrate portions of the intelligent vehicle terminal that form no part of the claimed design.

1 Claim, 8 Drawing Sheets
